[57] CLAIM

The ornamental design for a weighted exercise harness, as shown and described.

DESCRIPTION

FIG. 1 is a top plan view of a weight exercise harness showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a bottom plan view thereof;

FIG. 7 is a right side elevational view of a modified embodiment thereof;

FIG. 8 is a front elevational view of FIG. 7;

FIG. 9 is a rear perspective view of a second modified embodiment thereof; and,

FIG. 10 is a rear perspective view of FIG. 1.

FIG. 1

FIG. 2

FIG. 4

FIG. 3

FIG. 5

FIG. 6

FIG. 8

FIG. 7

FIG. 9

FIG. 10
